UNITED STATES PATENT OFFICE.

GEORGE J. MARTIN, OF NEWTON, MASSACHUSETTS.

DESIGN FOR A CURTAIN.

46,912.

Specification for Design.

Patented Feb. 2, 1915.

Application filed September 9, 1914. Serial No. 860,943. Term of patent 7 years.

To all whom it may concern:

Be it known that I, GEORGE J. MARTIN, a citizen of the United States, residing at Newton, in the county of Middlesex and State of Massachusetts, have invented a new, original, and ornamental Design for Curtains, of which the following is a specification, reference being had to the accompanying drawing, forming a part thereof.

Figure 1 is a plan view of a portion of a

curtain, illustrating my new design; and Fig. 2 is an enlarged detail.

I claim:

The ornamental design for a curtain, as shown.

GEORGE J. MARTIN.

Witnesses:

MARION EATON,
GRACE SULLIVAN.
